BAG POCKET

Isaac W. Rohatyn, New York, N. Y.

Application May 20, 1935, Serial No. 22,336

4 Claims. (Cl. 2—247)

This invention relates generally to pocket walls of the expandible type and more particularly to walls wherein the same are adaptable for use in both garments and hand bags.

5 The main object of the invention resides in the provision of a pocket wall structure adapted to carry the weight of articles in such manner as not to cause the mouth of the pocket to gap open, and where the said pocket wall structure is used in conjunction with a garment, the said structure serves to mitigate the distortions of the garment at the pocket.

10 A further object of the invention resides in the simplicity of construction of the said pocket wall and in the economy of manufacture and assembly of the same with accompanying structure.

15 These objects and other incidental ends and advantages of the invention will hereinafter appear in the progress of the disclosure and as pointed out in the appended claims.

20 Accompanying this specification is a drawing showing two adaptations of the preferred form of the invention, the said drawing being comprised of several views wherein corresponding reference characters designate corresponding parts throughout the several views.

According to the drawing:

25 Figure 1 is a view in perspective showing the improved pocket wall as affixed to any garment such as a skirt.

Figure 2 is a view in section of Figure 1 along the plane 2—2 thereof.

30 Figure 3 is a view in perspective showing the improved pocket wall as constituting the side walls of a hand bag.

Figure 4 is a view in section of Figure 3 along the plane 4—4 thereof.

35 In accordance with the invention and in accordance with the preferred forms thereof shown in the accompanying drawing, numeral 10 represents a garment such as a skirt showing a pocket wall attached thereto. It is understood, however, that any other garment other than a skirt may be used in conjunction with the said pocket wall. Numeral 11 designates a piece of fabric or other suitable material constituting the pocket wall and is provided with a series of plaits or folds. The said plaits or folds are divided into 40 two groups one group constituting folds 13, 14, 15, 16 and 17 and the other group constituting folds 18, 19, 20, 21 and 22. The folds proceed from the upper edge of fabric 11 on both sides of the central vertical axis and terminate along 45 the said central vertical axis, folds 13 and 22,

being the outermost of the two groups, extend to a point proximate to the lower edge of fabric 11. The said folds are stitched in place by means of a line of stitching at the upper edge of fabric 11, the said line of stitching being designated by numeral 33'. The upper edge of fabric 11 is hemmed in the normal manner for the usual purposes. The lateral and bottom edges of fabric 11 are stitched to skirt 10 by means of stitching 27 and 28, the lateral edges being gathered as shown by numerals 25 and 26 in Figure 2 in order that the pocket wall when in distended position will not exert too much of a pull on the skirt or other garment to which the pocket is stitched. Numeral 12' represents the inner wall of the pocket and is not provided with folds since the fabric of the skirt 12 is not expandible. Inner wall 12' may be omitted entirely, the fabric of skirt 10 superposed by pocket 11 serving the purpose thereof.

20 By virtue of the arrangement of folds 13—22 inclusive, a pocket wall is provided whereby a pushing out of the same by articles contained therein is compensated by a differential yielding of the pocket. Such differential yield of the 25 pocket prevents distorted opening of the mouth and minimizes the amount of opening altogether when bulky articles are inserted therein.

Plaits 13—22 inclusive, if desired are capable of being pressed to present a flat appearance when 30 not in distended position.

Figures 3 and 4 show a pocket wall 12 operating in conjunction with wall 11. The said pocket wall is similarly provided with two groups of folds, the individual folds being designated by 35 numerals 13'—22' inclusively and respectively. The walls 11 and 12 are stitched together at the lateral edges by stitching 23 and 24 and along the bottom edges by a row of stitching not shown in the drawing. The upper edges of walls 11 and 12 are each provided with stiffening elements 29 and 30 inserted in hems therein, the 40 said stiffening elements being resilient to permit the opening of walls 11 and 12 for insertion. As shown, however, the stiffening elements are provided with means intermediate the ends thereof, such as hinges, to permit facile opening of the two walls 11 and 12 constituting a hand bag. A handle 31 is provided and is connected to the walls 11 and 12 by means of 45 loop cords 32 and 33 penetrating the said walls. Thus, a hand bag has been constructed utilizing the improved pocket wall hereinbefore described. To place bulky articles in such hand bag, the mouth thereof is opened, the folds yield 50 55

to the massiveness of the said articles while the weight thereof brings about a closing of the hand bag when the weight depends from the handle 31.

5 It is understood that in the utilization of the improved pocket with a garment, a stiffener may be employed in the upper edge of the said pocket and a closure means such as a zipper may be provided.

10 I wish it distinctly understood that minor variations and modifications in the construction of the improved pocket wall as relates to the number of folds, the position thereof, the integration and material of parts may all be 15 sorted to without departing from the scope of the invention and without departing from the limits of the appended claims.

I claim:

1. An expandable pocket wall for attachment 20 to another surface, comprising a body portion, having top, side and lower edges, the said body portion being provided with a group of folds on each side of the central vertical axis of the said body portion, each group of folds extending from 25 the upper edge of the said body portion to the said central vertical axis, the lower terminal of each fold lying substantially along the said central vertical axis, the folds being stitched to the upper edge of the said body portion, the said body portion being adapted to be stitched to another surface along the side and bottom walls.

2. In a garment, an expandable pocket wall comprising a body portion, having top, side and lower edges, the said body portion being provided with a group of folds on each side of the 30 central vertical axis of the said body portion,

each group of folds extending from the upper edge of the said body portion to the said central vertical axis, the lower terminal of each fold lying substantially along the said central vertical axis, the folds being stitched to the upper edge 5 of the said body portion, means of attachment to the garment.

3. In a garment, an expandable pocket wall comprising a body portion, having top, side and lower edges, the said body portion being provided with a group of folds on each side of the central vertical axis of the said body portion, each group of folds extending from the upper edge of the said body portion to the said central vertical axis, the lower terminal of each fold 10 15 lying substantially along the said central vertical axis, the folds being stitched to the upper edge of the said body portion, means of attachment to the garment, and stiffening means affixed to the upper edge of the said body 20 portion.

4. A pocket form of two similar expandable walls attached to each other, each pocket comprising a body portion, having top, side and lower edges, the said body portion being provided with a group of folds on each side of the central vertical axis of the said body portion, each group of folds extending from the upper edge of the said body portion to the said central vertical axis, the lower terminal of each fold 25 30 35 lying substantially along the said central vertical axis, the folds being stitched to the upper edge of the said body portion, the said body portions having means of attachment to each other along the side and lower edges. 35

ISAAC W. ROHATYN.
